Primary Examiner — Sandra S Snapp*Assistant Examiner* — Mehri F Bajoul(74) Attorney, Agent, or Firm — Andrus Intellectual Property Law, LLP(57) CLAIM

The ornamental design for a billiard table, as shown and described.

DESCRIPTION

FIG. 1 is a perspective view of a billiard table.

FIG. 2 is a side view thereof.

FIG. 3 is an opposite side view thereof.

FIG. 4 is an end view thereof.

FIG. 5 is an opposite end view thereof.

FIG. 6 is a top view thereof; and,

FIG. 7 is bottom view thereof.

The broken lines represent portions of the billiard table that form no part of the claimed design.

1 Claim, 7 Drawing Sheets---
